UNITED STATES PATENT OFFICE.

WILLIAM D. BALLERSTEDT, OF LOS ANGELES, CALIFORNIA.

SPRAY-NOZZLE.

1,310,938.

Specification of Letters Patent. Patented July 22, 1919.

Application filed August 22, 1916. Serial No. 116,385.

To all whom it may concern:

Be it known that I, WILLIAM D. BALLERSTEDT, a citizen of the United States, residing at Los Angeles, in the county of Los Angeles and State of California, have invented a new and useful Improvement in Spray-Nozzles, of which the following is a specification.

My invention relates especially to lawn 10 sprinkler heads; and consists of the novel features herein shown, described and claimed.

The accompanying drawings illustrate the invention.

15 Figure 1 is an elevation of a spray nozzle or lawn sprinkler head embodying the principles of my invention, the water connection being broken away.

Fig. 2 is a vertical central section on the line x^2 , Figs. 3 and 4.

Fig. 3 is a vertical section on line x^3 , Figs. 2 and 4.

Fig. 4 is a horizontal section on line x^4 , Fig. 3, and looking upwardly.

25 Fig. 5 is an elevation of the adjustable vortex plug or head removed from the vortex housing or sprinkler head.

Fig. 6 is a top plan view.

The upper end of the water connection or 30 stand-pipe 1 has external screw threads 2 and an end face 3.

The sprinkler head 4 has a straight screw-threaded bore 5 extending from the lower end and fitting the screw threads 2, said 35 bore having a flat top surface 6 forming the lower side of the diaphragm 7 having the central discharge orifice 8 and the dished upper side 9 around the orifice. The sloping scalloped rim 10 extends outwardly from 40 the rim of the dished surface 9 and serves as a hand-hold for manipulating the sprinkler head, so that the head may be readily screwed on or off and up or down on the water connection.

45 The vortex plug 11 is exteriorly screw-threaded to fit in the screw-threaded bore 5 and has a slightly conical upper face 12 forming the lower side of the vortex chamber 13, which is thus reduced from the wall 50 of the bore toward the orifice and said plug has two spiral channels 14 and 15 in its periphery, said channels being tapered from the bottom upwardly, so as to cause a speedy, vertical discharge of the water into the vortex chamber and to reduce the volume of

water in the vortex chamber toward the outlet of the nozzle so as to discharge the water through the orifice 8 in a conical sheet, which whirls at a comparatively great speed and is thus capable of covering a large area 60 of ground. The annular flat lower face 16 of the plug 11 fits against the face 3 of the water connection, and closes the lower ends of the channels 14 and 15 so that when the head is screwed down the water is shut off 65 and by manipulating the head the volume of water is regulated to control the spray. A stem 17 extends from the center of the lower face of the plug and has a screw-driver slot 18, so that by removing the head from the 70 stand-pipe the plug may be adjusted up and down as desired to regulate the vortex chamber.

In actual practice the vortex plugs are set, and the sprinkler heads are screwed 75 upon the stand-pipes, and the only manipulation required is to screw the sprinkler heads up or down to get the desired spray from the water pressure as it exists for the tract to be covered. There are usually several nozzles on a line of pipe and it is desired to shut some of them off without shutting others off. This is done by screwing the heads down tight.

It is obvious that my spray nozzles may 85 be used for other purposes than lawn sprinklers.

I claim:

1. The combination with an externally screw-threaded connection leading from a 90 liquid supply source, of a spray nozzle comprising a sprinkler head having at one end a diaphragm which is provided with a central orifice therein and an inner flat surface, and a bore, cylindrical throughout its length 95 and extending from the other end of the head to the inner surface of the diaphragm and being coaxial with the orifice, the bore having screw threads which fit the threads of the connection so that the head is thereby 100 adjustably attached to the connection; and a vortex plug adjustably mounted in the bore and adapted to form between one end of the vortex plug and the inner surface of the diaphragm a vortex chamber which is 105 reduced from the wall of the bore toward the orifice, the vortex plug also having spiral peripheral channels which lead taperingly from the other end of the vortex plug to the vortex chamber, and the liquid sup- 110

ply to the nozzle being regulated by adjusting the head toward or away from the end of the connection and being entirely shut off when the last-named end of the vortex 5 plug is seated upon the end of the connection.

2. The combination with an externally screw-threaded connection leading from a liquid supply source, of a spray nozzle comprising a sprinkler head having at one end a diaphragm which is provided with a central orifice therein and an inner flat surface, and a bore, cylindrical throughout its length and extending from the other end of the 10 head to the inner surface of the diaphragm and being coaxial with the orifice, the bore having screw threads which fit the threads of the connection so that the head is thereby 15 adjustably attached to the connection; and a vortex plug adjustably mounted in the bore and adapted to form between one end of the vortex plug and the inner surface of the diaphragm a vortex chamber which is reduced from the wall of the bore toward 20 the orifice, the vortex plug also having spiral peripheral channels which lead from the other end of the vortex plug to the vortex chamber, and the liquid supply to the nozzle being regulated by adjusting the head 25 toward or away from the end of the connection and being entirely shut off when the last-named end of the vortex plug is seated upon the end of the connection.

3. The combination with an externally

screw-threaded connection leading from a 35 liquid supply source, of a spray nozzle comprising a sprinkler head having at one end a diaphragm which is provided with a central orifice therein and an inner flat surface, and a bore, cylindrical throughout its length 40 and extending from the other end of the head to the inner surface of the diaphragm and being coaxial with the orifice, the bore having screw threads which fit the threads of the connection so that the head is thereby 45 adjustably attached to the connection; and a vortex plug having a slightly conical end and being adjustably mounted in the bore so that the conical end is turned toward the inner surface of the diaphragm and thus forms 50 between the conical end and the inner surface of the diaphragm a vortex chamber which is reduced from the wall of the bore toward the orifice, the vortex plug also having spiral peripheral channels which lead 55 from the other end of the vortex plug to the vortex chamber, and the liquid supply to the nozzle being regulated by adjusting the head toward or away from the end of the connection and being entirely shut off when the 60 last-named end of the vortex plug is seated upon the end of the connection.

In testimony whereof I have hereunto set my hand at Los Angeles, California, this 28th day of July, 1916.

WILLIAM D. BALLERSTEDT.
